UNITED STATES PATENT OFFICE.

MITCHELL D. PRICE, OF MIAMI, FLORIDA.

CAN OPENER.

1,410,837.

Specification of Letters Patent. Patented Mar. 28, 1922.

Application filed May 10, 1921. Serial No. 468,259.

To all whom it may concern:

Be it known that I, MITCHELL D. PRICE, a citizen of the United States, and a resident of Miami, in the county of Dade and State of Florida, have invented certain new and useful Improvements in Can Openers, of which the following is a specification.

My invention relates to can openers and particularly to a device of this type which will be made strong and durable, coupled with simplicity of structure and operation.

The further object of my invention is to provide a can opener which can be used equally as advantageously for the opening of either round or square cans. Furthermore, the improved feature of this invention is the provision of a structure wherein the blades are made renewable thereby providing for the removal of a worn or broken blade.

A still further object of my invention is to provide a can opener which will be adjustable whereby the device may be used with equal advantage upon cans of various sizes.

The various features of my invention and the manner in which the same is used will be made more apparent in the accompanying specification and drawings in which:

Fig. 1 is a perspective view of a can opener constructed in accordance with my invention, as it is used when removing the tops of round cans,

Fig. 2 is a similar view showing the device as it is used when removing the tops of square cans,

Fig. 3 is a disassembled perspective view of a portion of the structure illustrated in Fig. 1,

Fig. 4 is a side elevation of the device with a slightly modified form of adjusting means,

Fig. 5 is an enlarged detailed section of the adjusting means shown in Fig. 4,

Fig. 6 is a fragmentary elevation showing still another modified form of adjusting means,

Fig. 7 is a fragmentary view of one portion of the device showing a modified manner of securing the blades thereto, and

Fig. 8 is a similar view of another modification.

Referring now more particularly to Figs.

1 to 3, it would seem that the device comprises a grip or handle portion 10 provided with bowed flexible sides 11 which are preferably thin to enable them to be suitably flexed while adjusting the device, but of a sufficient transverse width to provide sufficient rigidity during the cutting operation.

The flexible sides 11 terminate in enlarged free ends 12. These ends are slotted as shown at 13 (see particularly Fig. 3) thereby forming a forked or bifurcated end into which is adapted to be inserted either the knife 14 or the point 15. In any event the knife or point is provided with a flattened head 16 apertured as at 17 to register with two oppositely disposed apertures 18 formed at each bifurcated end of the device. A bolt 19 and nut 20 cooperate to secure either the knife or point in position.

In order to adjust the distance between the points 15 and the cutting knife 14, I provide in the structure illustrated in Figs. 1 and 2, a bolt 21 provided with a thumb wheel 22. The bolt 21 is provided with oppositely disposed screw-threads which engage threaded apertures in the enlarged ends 12 of the body of the device. It consequently follows that by suitably adjusting the bolt 21 by means of the thumb wheel 22 the distance between the point 15 and the cutting knife 14 may be regulated, thereby enabling the device to be used upon cans of varied sizes.

Formed preferably integrally with the body of the device and in alignment with the grip 10 there is a cutting blade 23 and an abutment 24. The end of the abutment 24 lies in substantial alignment with the portion of the bowed side which is comparatively thick and which is disposed immediately adjacent the grip 10. The blade 23 is employed in cutting the tops from square or oblong cans such as illustrated in Fig. 2 and this manner of operation will be more fully hereinafter described.

In Figs. 4 and 5, I have illustrated a slightly modified form of the means for adjusting the distance between the operative ends of the device. In this form a turn-buckle 25 cooperates with a pair of bolts 26, the ends of which are fastened to the enlargements 12 of the body of the device. The

pair of bolts 26 are provided with screw-threads of opposite pitch which cooperate with the turnbuckle 25 so that upon suitable rotation of the turnbuckle 25 the distance between the point 15 and the cutter 14 will be adjusted.

In Fig. 6, I have illustrated still another form of adjusting means. In this form a bolt 27 is secured against rotation by a head 28 in one of the enlargements 12 of the body of the device. The other end extends through an opening 28 in the other enlargement 12. The bolt is screw-threaded to receive a thumb nut 29 the distance between the point 15 and the knife 14 may be likewise adjusted.

Instead of securing the blade and point to the body of the device in the manner described hereinbefore, either or both may be secured in the manner illustrated in Fig. 7. In this figure the point 15 is shown as provided with a screw-threaded shank 30 which engages a correspondingly screw-threaded socket 31 formed in the enlarged portion 12 of the body of the device. Hence, a rigid connection between either the knife or the point and the enlargements 12 of the body of the device may be provided and the point or knife be made likewise removable.

In Fig. 8 I have illustrated still another modification wherein the point 15 is shown as formed integrally with the enlargement 12 of the body of the device. It is obvious that, should it be desired, either or both the point and knife may be formed integrally with the body of the device thereby eliminating some extra parts in the manufacture of the same. It is obvious that in many instances it will be unnecessary to form the point 15 separately from the body of the device, inasmuch as it is desirable mainly, to replace the knife 14 upon which most of the wear occurs.

Referring now to Fig. 1, the manner of operating the device will be briefly described:

In this figure a can C of usual form is shown. The distance between the center of the can and the circumferential path upon which it is desired to make the cut is gauged and the end of the device adjusted accordingly by suitably rotating the thumb wheel 22. The device is then grasped by the grip 10 and the point 15 forced into the center of the can. At the same time, the knife 14 is forced through the top of the can. By suitably rotating the device about the point 15 as a pivot, the top of the can may be cut out.

In Fig. 2 the manner in which the device is used while removing the top of a square or oblong can D is illustrated. During this operation, the device is turned on its side and the blade 23 pushed into the top 65 of the can until the abutment 24 contacts

with the top of the can. As stated hereinbefore, the end of the abutment 24 is in substantial alignment with the side 11 of the device. Consequently as the abutment 24 contacts the top of the can, the side 11 will 70 simultaneously contact the edge of the can. The operator then presses down on the grip 10 thereby swinging the blade 23 upwardly, the abutment 24 and side 11 acting as a fulcrum. This pressure is continued until 75 the blade 23 has cut upwardly through the top of the can, when the device is moved forward and the operation repeated. It consequently follows that, after several repeated operations, the top of the can will 80 be cut out.

The construction of the device is such that it may be cheaply manufactured, coupled with durability of service.

The operation of the device is exceedingly 85 simple, at the same time retaining effectiveness. The life of a device constructed in accordance with my invention is manifoldly greater by reason of the cutting blades being renewable as may also be the 90 points.

The structure and operation of my device having been described, what I claim is:

1. A can opener of the class described comprising a rigid handle, flexible side 95 members depending from said handle and provided with a point and cutter blade respectively and means for flexing said side members to adjust the distance between said point and cutter blade.

2. A can opener of the class described comprising a handle, a pair of flexible side members secured thereto, a point and blade secured to said side members and means for adjusting the distance between 105 the same.

3. A can opener of the class described comprising a rigid handle, two flexible side members, a cutting blade and point secured to said side members and means connecting the ends of said side members whereby the distance between the same may be adjusted.

4. A can opener of the class described comprising a rigid handle, two bowed flexible side members formed with said handle and terminating in two free ends, a blade and point secured to said free ends and means connecting said free ends, whereby the distance between said point and cutting blade 120 may be adjusted.

5. A can opener of the class described embodying a rigid handle and a pair of side members, an abutment secured to said handle, the end of said abutment being in 125 substantial alignment with one of said side members and a cutting blade rigidly secured to said abutment and in longitudinal alignment with said handle whereby said abutment and said members will simultane- 13

ously engage the top of a can, substantially as and for the purpose described.

6. A can opener of the class described comprising a rigid handle, a pair of bowed flexible side members formed therewith, said side members terminating in enlarged ends, means for removably securing

a point and cutting blade to said enlarged ends respectively and means connecting said enlarged ends whereby the distance between 10 said point and cutting blade may be adjusted.

MITCHELL D. PRICE.
